New York, N. Y., a corporation of New York

Application September 28, 1935, Serial No. 42,599

6 Claims. (Cl. 178—68)

This invention relates to communication systems and more particularly to printing telegraph systems of the non-synchronous type. The principle of the system employed in the present invention instead of depending on the synchronous operation of the transmitting and receiving units operates on the basis of the transmission of signals of predetermined current values to which the receiving unit will give a definite and different response to each signal. A system of this type is fully disclosed and described in a copending application, Serial No. 737,013, filed July 26, 1934.

The present invention is in the form of an improvement of the system described in the aforesaid application. Briefly and broadly, the system in said application comprises a transmitting unit to initiate character signals consisting of code combinations of impulses having differential current values and polarity. The receiving unit includes relay devices sensitive to said impulse characteristics to control the selection of different circuits, for example, a galvanometer relay of the d'Arsonval type may be used to respond to the different current values employed and the polarity of the impulses, so that the relay brush or armature is positioned to engage one of a plurality of contacts in accordance with the characteristics of the character signal. In addition thereto, another relay device may be used to be responsive only to the number of impulses included in the code combinations, in turn, controlling a device such as a relay to be operated step by step such as the well known type of stepping relay.

A plurality of circuits are associated with the galvanometer relay contacts and with the contacts of the stepping relay and are arranged so that upon the respective positioning of the galvanometer relay and the stepping relay, a single circuit corresponding to the character signal is selected to be energized effecting registration of the selected character.

An object of the present invention is to provide individual control devices adapted to be responsive successively to the signal impulses and to effect selection of the particular circuits upon each energization thereof in accordance with the signal impulses transmitted.

Various other objects and advantages of the invention will be obvious from the following particular description of one form of mechanism embodying the invention or from an inspection of the accompanying drawings; and the invention also constitutes certain new and useful

features of construction and combination of parts hereinafter set forth and claimed.

In the drawings:

Fig. 1 is a schematic diagram showing one form of the connections of the impulse transmitter. 5

Fig. 2 is a preferred form of the code used in conjunction with the present invention.

Fig. 3 is a schematic diagram showing one form of circuit arrangement of the receiving system. 10

Referring now to Fig. 1, a plurality of pulse wheels or disks 14 are shown with a combination of conducting segments 16 thereon. The arrangement and number of conducting segments for each disk corresponds to the code shown in 15 Fig. 2, for example, the character "S", the code of which is current value 1, positive polarity and four impulses, namely, three short impulses and one long impulse. Therefore, on the disk 14 for the character "S", for conducting segments 16 20 are disposed thereon so that the three short pulses of current are conducted before the long segment engages the contacts 17 to transmit the long impulse of its corresponding current value. 25

It is to be noted that for characters represented by a plurality of impulses the last impulse is always a long impulse the significance of which will be understood as the description progresses. Each disk therefore has disposed thereupon the number of segments to correspond to the number of impulses in its particular code. It is sufficient to mention that upon depression of a character key of the typewriter (not shown) its corresponding disk 14 is released to complete one revolution, thereby conducting the proper increment of current value, polarity and the number of impulses representing the character, to the connected line network. A further description of the transmitting system may be had by referring to the said prior application in which the transmitting typewriter and mechanism for releasing the pulse wheels is shown and completely described. Since this mechanism forms no part of the invention, it is deemed unnecessary to repeat such description. 35

With reference now to Fig. 3, the code combination of impulses consisting of predetermined characteristics are received over the line associated with the galvanometer relay 20 and line relay 21. The galvanometer relay 20 is shown to comprise an energizing coil 22 connected directly across the line and adapted to be energized in accordance with the various current strengths and polarity of the impulses impressed thereupon to control the positioning of the armature 23 with 40 45 50

respect to the associated contacts 24. It is to be noted that eight contacts 24 are provided, four contacts corresponding to the four increment current values of positive polarity and four contacts 5 for the four negative current values. The said relay 20 is adjusted so as to be sensitive to the current strength and polarity of the impulses and not to the number of the impulses transmitted. The short impulses impressed on the 10 coil 22 are not of sufficient duration to properly position or actuate the movable armature 23 to the proper contacts 24. However, the long impulse which is the last impulse transmitted in the selected code is of sufficient duration to cause 15 the armature 23 to engage the proper contact 24 corresponding to the current value and polarity of the impulses transmitted. Therefore, when and only when the long impulse is transmitted is the relay 20 energized sufficiently to be properly positioned so that the armature 23 can supply 20 current to the selected circuit connected to the particular contact 24. To continue with the example, for character "S" the armature 23 is positioned to contact 24-1 of the positive group 25 of contacts, upon reception of the last and long impulse of the group of impulses therefor, for it is remembered that the code combination of the said character is four impulses (three short impulses and one long impulse) of the first current 30 value and positive polarity.

The armature 23 upon being properly positioned connects battery to the corresponding relay of the group of relays 25 associated with the particular contact 24. Assuming the armature 23 35 is to be positioned in engagement with contact 24-1 grounded battery 26 is connected to relay 25-4 energizing said relay and closing the associated contact 27-4. Current from grounded battery 26 then energizes the associated control 40 relay 28-4 thereby connecting a predetermined group of circuits to ground through the now closed contacts *a* to *d*. The description will now be set forth to perform a further selection from the said group of circuits so as to select and 45 energize a single circuit thereof, for the example set forth in the present description, the single circuit to be selected corresponds to the character "S".

It was mentioned hereinbefore that the relay 50 21 is sensitive to the number of impulses only and therefore it is to be understood that it responds to both the short and long impulses transmitted over the line. Control circuits are provided to be conditioned so that upon the transmission of a first impulse, relay 31 is adapted to be energized and thereby effecting a particular group or further selection from a predetermined group of circuits selected by the operation relay 20. Operation of relay 31 conditions a control 55 relay 35 so that upon the receipt of a second impulse, relay 32 is energized and another particular group of circuits is selected. Operation of relay 32 conditions a control relay 36 so that the reception of a third impulse energizes relay 33 and selects a third particular group of circuits and also conditions control relay 37 so that a 60 fourth impulse energizes relay 34 and selects a fourth group of particular circuits to complete a further selection operation.

Assuming now that the relay 21 is energized by 70 the first impulse of the group of impulses included in the code for the character "S". Grounded battery 40 is connected to contact 41 (now closed), conductor 42, normally closed contact 43, conductor 44, normally closed contact 45, conductor

46, normally closed contact 47, conductor 48 and grounded relay 31, energizing said relay. Connecting battery 40 to contact 49 also effects a particular group selection of circuits, namely the circuits associated with the common conductor 50. Referring to the code signal for character "S" 5 it is seen that a single circuit selection is not effected owing to the fact that the armature 23 is not positioned during the reception of the first impulse of the representative group of impulses. 10

Operation of relay 31 permits a locking circuit to be established for the said relay as follows: Grounded battery 40 is connected through normally closed contact 51, conductor 52, normally closed contact 53, conductor 54, normally closed contact 55, conductor 56, normally closed contact 57, conductor 58, contact 49 now closed and grounded relay 31. Upon de-energization of relay 21, that is, upon completion of the transmission of the first impulse of the code combination of impulses, grounded battery 40 is connected by conductor 59, through normally closed contact 60, conductor 61, contact 62 (now closed), conductor 63 and grounded relay 35, energizing the said relay. A locking circuit for the last 20 mentioned relay is then established by connecting grounded battery 40 through the normally closed contact 51, contact 64, now closed, and the grounded relay 35. 25

It will now be evident that energization of 30 relay 21 upon receipt of the second impulse connects grounded battery 40 to relay 32 through contact 41, conductor 42, normally closed contacts 43 and 95 and contact 65 now closed, energizing relay 32 and also connecting battery to 35 contact 65 and the group of circuits associated with common conductor 66. Again further selection of a single circuit from the last mentioned predetermined group of circuits is not effected, since relay 20 is not responsive to the short pulses 40 transmitted. A locking circuit is established to maintain relay 32 energized as follows: from grounded battery 40, to contacts 51, 53, 55 and 65. Energization of relay 32 opens the contact 57 to break the locking circuit described for 45 relay 31 causing the said relay to be deenergized. Therefore, upon de-energization of relay 21, grounded battery 40 is connected to relay 36 through contacts 60, 67 and 68 to energize relay 50 36 and establish a locking circuit for this relay by connecting grounded battery 40 through contacts 51 and 69 and grounded relay 36.

In a like manner, energization of relay 21 upon 55 reception of the third impulse causes the relay 33 to be energized and establish a locking circuit therefor, supplying current to a group of circuits associated with the contact 70, but, as understood, a further single selection can not be effected at this time. Energization of relay 33 breaks the locking circuit just described for 60 relay 32 and deenergizes the said relay.

Deenergization of relay 21 similarly energizes 65 relay 37 and establishes a locking circuit for the said relay which conditions circuits similar to those just described, so that upon the fourth energization of relay 21 due to the reception of the fourth signal impulse, battery 40 is connected through contact 71 now closed to energize relay 34 and establish a locking circuit therefor through contact 72. Opening of contact 53 breaks the 70 locking circuit for relay 33 causing said relay to be de-energized which is now understood without further description. Grounded battery 40 is then connected through the normally closed contacts 51, conductor 52, contacts 75 now closed and im- 75

pressed on the predetermined group of circuits connected to and associated with common conductor 76.

Referring now to the code in Figure 2, the fourth impulse of the code combination for character "S" is a long impulse, the transmission of which in addition to energizing relay 21 effecting the energization of relay 34 and deenergization of relay 33, simultaneously causes the armature 23 of relay 20 to be positioned properly in accordance with the current characteristics, which for the character "S", as explained hereinbefore is the position to effect engagement of the armature 23 and contact 24-1 of the positive group of contacts.

It has been shown that such positioning of the said armature selects and causes control relay 28-4 to be energized, closing contacts *a* to *d* concomitantly with the closing of contact 75.

Upon completion of the operation just mentioned, it is evident that grounded battery 40 can only be effective to energize and operate a single circuit, namely the circuit corresponding to character "S", which is as follows: grounded battery 20 40 to normally closed contact 51, conductor 52, contact 75, now closed, conductor 76, solenoid 18 corresponding to the "S" solenoid, contact *a*, now closed, to ground. Referring to the drawing, it is seen that a solenoid 18 is included in each one of the circuits associated with the *a* to *d* contacts of the control relays 28; the said solenoids may be associated with a suitable recording or control unit, for example, such as a punch or typewriter and may be connected so that upon energization 35 the key bars of the particular recording unit are depressed accordingly to effect registration of the character. Further description of a suitable recorder is deemed unnecessary because a complete disclosure thereof may be had by referring 40 to the said aforementioned application.

Upon depression of the key bars and operation of the recording unit, common contacts 80 are adapted to be operated. Specific mechanism for this provision is not shown since it is old and well 45 known in the art; one method which has been used heretofore is to provide a common bar beneath the key bars of the typewriter and arranged so that the depression of the character key bars lowers the common bar which in turn causes the 50 common contacts to be closed.

Closure of contacts 80 permits grounded battery 81 to be connected to relay 38, energizing this relay thereby opening the associated contacts 51. Operation of contacts 51 disconnects grounded 55 battery 40 from the contacts 64, 69 and 82, through which it must be remembered the locking circuits for relays 35, 36 and 37 respectively were established. Therefore the said relays are deenergized and returned to the normal condition as 60 shown in the drawings. Similarly, grounded battery 40 is removed from contact 72 to break the locking circuit established for relay 34 thereby restoring the said relay to normal condition. It is evident from the description just set forth that 65 upon operation of the recording unit the conditioned control circuits for the relay selecting unit just described are all restored to the normal condition as shown in the drawings and in a condition to continue subsequent selection of character 70 circuits in accordance with the character signals. From the description just set forth regarding the selective relay circuits it is obvious that if the character code combination includes a number of impulses less than four impulses, the conditioning 75 and operation of the circuits is similar to the op-

eration just outlined and that irrespective of the number of impulses transmitted for the character signal, operation of the recording unit restores the conditioned circuits to normal similarly as described herein.

While there has been shown and described and pointed out the fundamental novel features of the invention as applied to a single modification, it will be understood that various omissions and substitutions and changes in the form and details 10 of the device illustrated and in its operation may be made by those skilled in the art without departing from the spirit of the invention. It is the intention therefore to be limited only as indicated by the scope of the following claims.

What is claimed is as follows:

1. In a communication system, means to transmit character signals comprising code combinations of impulses having different current values and polarity and number of impulses included in 20 the code, a plurality of circuits, means responsive solely to the current value and polarity of the impulses to select a predetermined number of circuits from said plurality of circuits and means responsive solely to the number of impulses included in said code to select certain circuits from 25 said plurality upon each energization thereof and to condition control circuits upon deenergization of the last mentioned means to permit further selection from said predetermined number of circuits upon a subsequent energization of said last mentioned means.

2. In a communication system, means to transmit character signals comprising code combinations of impulses having different current values 35 and polarity and number of impulses included in the code, a plurality of circuits, a plurality of control devices, means responsive solely to the number of impulses included in said code to control the successive energization of said control devices 40 to select predetermined groups of circuits from said plurality of circuits in accordance with the number of impulses in said code, and means responsive solely to the current value and polarity of the impulses to complete a further selection of 45 circuits from said predetermined group of circuits.

3. The invention set forth in claim 2 in which control circuits are provided to maintain the said control devices energized until the reception of 50 the subsequent impulse.

4. In a communication system, means to transmit character signals comprising code combinations of impulses having different current values and polarity and number of impulses included in 55 the code, a plurality of circuits, a plurality of individual relay devices responsive to and conditioned solely by the number of impulses included in said code to obtain step by step selection of certain groups of circuits from said plurality of 60 circuits and means responsive solely to the current value and polarity of the impulses to complete a further selection of circuits from said groups of circuit.

5. In a communication system, means to transmit signals comprising code combinations of impulses having different current values and polarity and number of impulses included in the code, a plurality of circuits, means responsive to the current value and polarity of the impulses and 70 means responsive solely to the number of impulses included in said code to select a particular circuit from said plurality of circuits, said last mentioned means including a plurality of individual relay devices and control circuits 75

therefor to obtain step by step circuit selection and to be conditioned during the transmission of the impulses to maintain the selection of the said particular circuit upon completion of the transmission of the character signal, a receiving device adapted to be operated by said selected circuit, and means to restore the conditioned

circuits to normal condition upon operation of said receiving device.

6. The invention set forth in claim 5 in which the last named means is operated directly by said receiving device.

JOHN D. JOHNSTON.
